(57) **CLAIM**

The ornamental design for a brake shoe with thermal management features, as shown and described.

DESCRIPTION

FIG. 1 is a perspective view of a first embodiment of a brake shoe with thermal management features;

FIG. 2 is an elevational view of a first side of the brake shoe with thermal management features;

FIG. 3 is an elevational view of a second side of the brake shoe with thermal management features;

FIG. 4 is an elevational view of a first end of the brake shoe with thermal management features;

FIG. 5 is an elevational view of a second end of the brake shoe with thermal management features;

FIG. 6 is a plan view of a top side of the brake shoe with thermal management features;

FIG. 7 is a plan view of a bottom side of the brake shoe with thermal management features;

FIG. 8 is a perspective view of a second embodiment of a brake shoe with thermal management features;

FIG. 9 is an elevational view of a first side of the brake shoe with thermal management features;

FIG. 10 is an elevational view of a second side of the brake shoe with thermal management features;

FIG. 11 is an elevational view of a first end of the brake shoe with thermal management features;

FIG. 12 is an elevational view of a second end of the brake shoe with thermal management features;

FIG. 13 is a plan view of a top side of the brake shoe with thermal management features; and,

FIG. 14 is a plan view of a bottom side of the brake shoe with thermal management features.
